UNITED STATES PATENT OFFICE.

CHARLES E. CLARK AND ARCHIE G. DOWELL, OF SAN FRANCISCO, CALIFORNIA; SAID DOWELL ASSIGNOR TO SAID CLARK.

ELECTRIC HEATER.

1,327,986.

Specification of Letters Patent. Patented Jan. 13, 1920.

Application filed February 26, 1919. Serial No. 279,267.

To all whom it may concern:

Be it known that we, CHARLES E. CLARK and ARCHIE G. DOWELL, both citizens of the United States, residing at San Francisco, in the county of San Francisco and State of California, have invented new and useful Improvements in Electric Heaters, of which the following is a specification.

This invention relates to an electric heating device.

It is the principal object of this invention to provide an electric heater which is economical in its construction and which may be conveniently used for heating the rooms of dwellings and like places by electricity, said heater being especially designed to prevent direct radiation of the heat from the heating element and to insure that it will be uniformly distributed over a large area surrounding the heating structure, thereby establishing a larger zone of heat radiation than is commonly produced by heaters of the direct heating or reflecting type.

The present invention contemplates the use of a central core upon which is mounted the heating element and which element is inclosed within a heat distributing casing, this casing also inclosing heat reflectors adapted to assist in preventing the radiation of heat to the electric fixture or the socket carried by the device, the heat casing being furthermore inclosed within a protective cage and all of the various elements designed to be readily assembled by a single simple fastening member.

The invention is illustrated by way of example in the accompanying drawings, in which the figure indicates a central vertical section through the complete structure, illustrating all of the elements of the device and further showing one of the reflectors in elevation.

Referring more particularly to the drawings, 10 indicates a screw plug formed of dielectric material and fitted with a metallic screw and with suitable electrical contacts of common construction.

The lower portion of the plug 10 is enlarged and is provided with yieldable spring contacts 11 and 12, by which an attachment member 13 may be detachably secured thereby. The attachment member 13 is formed of dielectric material and carries a pair of spring fingers 14 and 15 within it. These fingers are adapted to frictionally engage

the fingers 11 and 12 previously referred to and will thus hold the plug 10 in engagement with the member 13. The spring fingers 14 and 15 are secured in position by means of screws 16 and 17 which pass through the end of the attachment member 13 and also through threaded openings in the fingers. A central counter-bored opening 18 is formed through the attachment member 13 and is adapted to receive an assembling bolt 19. The bolt 19 is formed with an enlarged head which hangs within the member 13 and supports the bolt so that the various elements of the heater may be strung thereon with resultant economical and commercial advantage.

Intermediate the length of the plug 10 is formed an annular groove 20. This groove is adapted to provide a seat for a conical canopy 21. The conical canopy 21 flares outwardly and downwardly and has an annular clamping flange 22 near its lower edge and therearound. Circumscribing this clamping flange is a cage ring 23. The cage ring may be provided with means for clamping it in position and securely held thereupon. This ring forms the upper part of an outer cage 24, carrying a series of longitudinally extending rods 25. The rods pass downwardly in parallel relation to each other and form a cylindrical cage, the lower end of which is closed by the convergence of the wires into a bottom fastening hub 26. It will be understood that other cage rings 24 may be placed around the rods in order to give it suitable reinforcement. Small fastening brackets 27 are secured around the inner face of the canopy 21 and also are fastened to the outer and upper edge of a heat casing 28. The heat casing 28 is here shown as formed of sheet metal and as having its entire body perforated, as indicated at 29. It will be understood that other foraminous material might be used as an inclosure to produce the desired effect. This effect is to prevent the direct radiation of heat and to cause it to be thoroughly distributed over a larger area than would be normally possible, at the same time thoroughly heating the casing and thus making it the radiating medium.

The lower end of the casing 29 is closed by a perforated end cap 30 through which the bolt 19 extends. Positioned upon the upper end of the bolt 19 is an insulating

tube 31. One end of this tube rests directly against the lower end of the connecting member 13 and the other end of the tube rests against an inverted conical reflector 32. 5 This reflector is here shown as formed of two-ply sheet metal between which a thickness of heat insulating substance is disposed. Directly beneath the reflector 32 is a heat insulating tube 33 which is also strung on 10 the bolt 19 and this tube bears against the upper inner face of a heat reflector 34, identical with the reflector 32. An insulating bead 35 is mounted upon the bolt 19 and forms a support for the reflector. The bead 15 35 is supported upon a metallic spider 36, resting directly upon the cylindrical core 37 of a heating element 38. The core 37 may be formed of any suitable dielectric material such as soapstone and the like. The 20 lower end of the core 37 is supported by a spider 39, similar to the upper spider 36. This spider rests directly upon the end 30 of the heat case. The lower end of the bolt 19 is threaded for considerable distance and 25 carries a fastening nut 40 adapted to bear against the end cap 30 of the heat case and hold all of the elements in rigid relation to each other upon the bolt. The extreme end of the bolt 19 extends through the hub member 26 and is there fitted with a small nut 30 41 which holds the structure completely in position. It will be noted that the bolt 19 forms the central member of the heating element and around this bolt all of the parts 35 may be disposed in their proper relation to each other and thereafter fixed by the positioning of the nuts 40 and 41, as previously described. Due to this arrangement, the problems of assembly will be materially 40 reduced and as the parts of the structure may be readily and inexpensively made, it will be evident that a very economical heating device will be provided. It will be understood that the heating element is supplied 45 with electricity by means of the lead wires 42 and 43 which extend upwardly through insulating bushings 44 and are secured to the screws 16 and 17 carried in the member 13.

50 In the operation of the device, the heating element will reach its predetermined heat, which in turn will radiate and will be absorbed and distributed by the heat casing.

While we have shown the preferred form 55 of our invention, it will be understood that various changes in the combination, construction and arrangement of parts may be made by those skilled in the art, without departing from the spirit of the invention, 60 as claimed.

Having thus described our invention, what we claim and desire to secure by Letters Patent is—

65 1. A cylindrical vertically suspended heater, comprising an electric plug and di-

vergent surrounding canopy, a dielectric member suspended from the plug, conducting wires extending from the plug through the dielectric member, a suspended heating coil with which the wires are connected, and 70 a foraminous cylindrical casing surrounding the heating coil.

2. A vertically suspended heater, comprising an electric plug, a divergent canopy suspended from the plug, a foraminous casing having its upper end fixed to the canopy, a dielectric member extending downwardly from the plug within the casing, conducting wires from the plug, a resistance coil within the casing with which the wires connect, 75 downwardly convergent reflectors above the coil and within the casing, and a central rod having its head suspended within the dielectric member and supporting the heating coil and the reflectors.

3. A heater of the character described, including an electric plug, a dielectric member, a resistance coil with which the wires connect, downwardly convergent reflectors above the coil, a central rod extending 90 through the said members, a foraminous casing by which said members are inclosed, screw threads upon the lower end of the rod, and adjusting nuts co-acting with the bottom of the casing to support and adjust 95 the inclosed members.

4. A heater including an electric plug, a dielectric member suspended therefrom, a resistance coil, wires connecting the plug with the coil, downwardly convergent reflectors above the coil, a rod having its head within the dielectric member, a foraminous inclosing casing within which the above-named members are contained and through 100 which the rod passes, with means to support and adjust the inclosed members, a downwardly divergent canopy supported from the plug and itself supporting the casing, and circumscribing parallel rods supported from the canopy with the lower ends curved 105 inwardly and united to a central hub secured to the suspending rod.

5. An electric heater comprising a connecting plug, an assembling bolt mounted within the plug, reflecting members strung 115 upon said bolt, a heating element through which the bolt passes, a heat casing inclosing said reflectors and the heating element, and means for tightening the casing, said reflectors and the element upon the bolt.

6. An electric heater comprising a connecting plug, an assembling bolt mounted within the plug, reflecting members strung upon said bolt, a heating element through which the bolt passes, a heat casing inclosing 120 said reflectors and the heating element, means for tightening the casing, said reflectors and the element upon the bolt, and a protecting cage secured in its assembled position by the bolt.

7. An electric heater comprising an attachment plug, a surrounding canopy, a heating coil suspended from said plug, electrical connections between said coil and plug and an apertured inclosing structure for said coil.

8. An electric heater comprising an attachment plug, a surrounding canopy, a heating coil suspended from said plug, electrical connections between said coil and plug, an apertured inclosing structure for

said coil, and heat reflecting means disposed above said coil and within said inclosing structure.

In testimony whereof we have hereunto set our hands in the presence of two subscribing witnesses.

CHARLES E. CLARK.
ARCHIE G. DOWELL.
